UNITED STATES PATENT OFFICE.

WILLIAM W. ARMINGTON AND HORACE A. BRIGGS, OF NORWICH, CONNECTICUT; SAID ARMINGTON ASSIGNOR TO SAID BRIGGS AND CHARLES W. HOPKINS, SAMUEL S. HOPKINS, AND CHARLES H. ALLEN, ALL OF SAME PLACE.

FIRE-ARM.

SPECIFICATION forming part of Letters Patent No. 429,110, dated June 3, 1890.

Application filed February 17, 1890. Serial No. 340,696. (No model.)

To all whom it may concern:

Be it known that we, WILLIAM W. ARMINGTON and HORACE A. BRIGGS, citizens of the United States, residing in the city of Norwich, county of New London, and State of Connecticut, have jointly invented certain new and useful Improvements in Fire-Arms, which improvements are fully set forth and described in the following specification, reference being had to the accompanying sheet of drawings.

The object of our invention is to provide a cheap, serviceable, and positive device for locking together the barrel and frame in that class of arms in which the barrel is turned down to fit a corresponding hole in the frame. In such arms, while it is necessary that the frame and barrel be securely fastened together when the arm is in service, it is also desirable that the barrel-fastening be of such a nature that said barrel may be quickly removed without the aid of special tools.

In the annexed drawings, Figure 1 is a side view of portions of a rifle frame and barrel, said parts being locked together by a screw-key fastening of our improved construction. Fig. 2 is a cross-section of Fig. 1 on line $x-x$. Fig. 3 is a detached view (somewhat enlarged) of our improved screw-key, and Fig. 4 a longitudinal sectional view of the same. Fig. 5 is an outer face view of the nut c^2 and its operating-handle, and Fig. 6 is a similar view of a nut formed substantially as an ordinary thumb-nut.

The letter a denotes the frame of an arm, b the barrel, and c the screw-key fastening as a whole.

The lock proper of our device consists of a pin or key c' , which is preferably slightly tapered, and which passes through the frame at a point where it intersects and cuts into the periphery of the barrel, as in Patent No. 14,491, issued March 25, 1856. In said patent the pin serves as a locking key or wedge that may be driven into or out of place to lock or release the barrel; but our present device differs from that of said patent in having connected with the locking pin or key means

whereby said key may be forced into place or easily withdrawn without the aid of a hammer or other tool. Further, our locking-key cannot by accident work loose and jar out of place. The outer (larger) end of our pin c' is shouldered down to enter a corresponding hole in a ring-shaped section c^2 , that is threaded on its periphery and adapted to screw into a threaded recess in frame a . The shouldered end of pin c' is fitted loosely in section c^2 and does not necessarily rotate with said section, but is prevented from leaving said section by a screw c^3 , that is tapped into the end of the pin, as indicated in dotted lines in Fig. 4. Projecting radially from the threaded section c^2 is an operating-handle, which I prefer to form as a simple lever c^4 , as illustrated in Figs. 1 to 5, although, if desired, two projections, substantially as in ordinary thumb-nuts, could be provided, such double form of operating-handle being shown in Fig. 6 of the drawings.

When it is desired to lock together the barrel and frame, our described screw-key is entered in the frame and the threaded section c^2 screwed home, which action forces the pin c' forward into its seat in both frame and barrel and prevents their separation until nut c^3 is again unscrewed.

To prevent the entire withdrawal of pin c' , (in which case it might be lost or misplaced,) we have tapped into frame a from its underside a screw d , whose end projects upward into a longitudinal groove e in said pin c' , the said groove being cut nearly but not quite to the end of the pin. When the pin is withdrawn, the end of screw d engages the end wall of groove e , and thus prevents the entire withdrawal of the locking-pin.

Having thus described our invention, we claim—

1. In combination with the frame and barrel of an arm of the class referred to, a locking-pin passing through the frame and across the barrel, and having revolubly secured to one end a threaded ring-section that may be screwed into a correspondingly-threaded recess in the frame, as set forth, said ring-sec-

tion being provided with an operating-handle, all being substantially as and for the purpose specified.

2. In combination with the frame and barrel of an arm, a longitudinally-grooved pin (passing across the barrel) and having revolvably secured to one end a threaded ring-section that may be screwed into a correspondingly-threaded recess in the frame, and a

screw tapped into said frame, with its end projecting into said longitudinal groove, all being as and for the purpose specified. 10

WILLIAM W. ARMINGTON.

HORACE A. BRIGGS.
